UNITED STATES PATENT OFFICE.

CHARLES MATTHEWS MANLY, OF FREEPORT, NEW YORK.

CONTROL APPARATUS FOR POWER-DRIVEN MECHANISM.

1,308,550.

Specification of Letters Patent.

Patented July 1, 1919.

Application filed October 11, 1911. Serial No. 654,129.

To all whom it may concern:

Be it known that I, CHARLES M. MANLY, a citizen of the United States, residing at Freeport, Long Island, New York, have invented certain new and useful Improvements in Control Apparatus for Power-Driven Mechanism, of which the following is a specification.

My invention relates to control apparatus for power driven mechanism and particularly to apparatus for controlling the driving mechanism of the revolving gun turrets employed in modern naval vessels.

The object of my invention is to provide simple and effective means in such mechanisms for enabling the operator to control the movements of the power driven mechanism, accurately and quickly and by substantially the same movement that the mechanism could be directly operated by hand were it light enough to be operated by moderate manual exertion. A further object of my invention is to provide a mechanism of the character described such that the operator may be stationed at a distant point from the position of the driving mechanism and yet control the mechanism as accurately and rapidly as if he were close at hand.

My invention further consists in various novel details of construction as will appear from the following specification and be pointed out in the appended claims.

In the accompanying drawings I have illustrated a preferred embodiment of my invention, and in the said drawings;

Figure 1 shows in vertical section, a gun turret having a driving mechanism equipped with my improved control apparatus.

Fig. 2 is a plan view partly in section of a portion of the driving and control mechanism.

Fig. 3 is a horizontal sectional view on the plane of the crank shaft of the hydraulic variable speed gear employed for operating the turrets.

Figs. 4 and 5 are detail views which will be hereinafter described.

Referring now to the drawings, in which like reference characters indicate like parts throughout the several views, 10 indicates portions of the frame work of the ship and 11 the deck thereof. Supported on the frame 10 is the stationary armor belt 12 which surrounds the circular track 13 of the turret. The turret comprises a rotary armor belt 14 having an armored roof 15

and supported by a frame work 16 carried by a circular bearing 17 resting on rollers 18 on the circular track 13. The guns 19 are supported in the turret by any suitable means not shown, and also carried by the turret on the floor 20 thereof is the driving mechanism for rotating the turret. This driving mechanism comprises an electric motor 21 driven from any suitable source of power not shown, and driving through a hydraulic variable speed gear 22, which will be later described, a shaft 23 provided with a worm 24 which meshes with a worm wheel not shown, on a vertical shaft 25 which extends through the floor of the turret, and carries a pinion 26 meshing with a stationary rack on the inner face of the circular track 13.

The hydraulic variable speed gear forms ⁷⁵ *per se* no part of the present invention and therefore only such parts thereof as are necessary to an understanding of the operation of my improved control mechanism will be specifically shown and described in this ⁸⁰ application. The gear selected for illustration is generally similar to the gear disclosed in my prior Patent #801,097 granted Oct. 3, 1905, and is identical with the gear disclosed in my prior Patent No. 85 1,206,453, granted November 28, 1916. It comprises a variable capacity multi-cylinder pump 27 adapted to be continuously and uniformly driven by the electric motor 21 and having fluid transmitting connections ⁹⁰ with a hydraulic motor 28 also of the multi-cylinder type which drives the shaft 23, so that the pump, motor and connections form a closed fluid circuit having a high pressure side and a low pressure side depending on ⁹⁵ the direction of flow of the fluid. Means are provided for varying the capacity of the pump from a maximum quantity flowing in one direction through zero to a maximum quantity flowing in the opposite direction. ¹⁰⁰ It will be obvious therefore that by adjusting the pump capacity the speed and direction of rotation of the motor may be varied as desired within the limits of the maximum forward and reverse speeds for which the ¹⁰⁵ mechanism is designed.

The pump 27 as shown in Figs. 2 and 3 comprises radial cylinders 30 provided with the usual pistons 130. The pistons are reciprocated by the shaft 31 which is coupled ¹¹⁰ to the shaft of the electric motor 21. The shaft 31 has a variable stroke crank pin con-

sisting of a crank pin 131 integral with the shaft and having an eccentric bushing 132 of equal eccentricity rotatably adjustable thereon. It will be obvious that when the 5 bushing is in one position of adjustment relatively to the crank pin the pump pistons will have a stroke equal to twice the eccentricity of the crank pin and when the bushing is adjusted around the crank pin the 10 stroke of the pistons will be reduced by imperceptible degrees until the bushing and crank pin counteract each other at a position 180 degrees angularly from the first mentioned position where the pistons will 15 have no stroke. If the adjustment of the bushing be continued in the same direction the stroke of the pistons will be gradually increased until at a point 360 degrees from the first mentioned position they will again 20 have their maximum stroke. The intake and delivery of fluid to and from the pump cylinders is controlled by piston valves working in valve chambers 32 connected to the cylinders by passageways 33 and means are provided for reversing the relative positions of the pistons and valves when the eccentric bushing is adjusted from one side to the other of its no-stroke or zero position, so 25 that when the eccentric bushing is adjusted 30 through 360 degrees the speed of the motor will be varied from full speed in one direction of rotation through all intermediate speeds to full speed in the reverse direction. For adjusting the eccentric bushing there 35 is provided a sleeve 133 rotatably mounted on the shaft 31 and operatively connected to the eccentric bushing by an internal gear 134 meshing with gear teeth cut in the adjacent end of the bushing. The portion of 40 shaft 31 surrounded by the sleeve is of smaller diameter than the interior diameter of the sleeve and is threaded as indicated at 135 to receive a nut 136 which nut is connected to the sleeve for rotation therewith 45 but for independent longitudinal movement by means of a series of shoes 137 attached to the nut and working in longitudinal slots 138 in the sleeve. A yoke 34 surrounds and 50 rotatably engages the nut so that longitudinal movement of the yoke will shift the nut along the thread of the shaft 31 and turn the eccentric bushing around the crank pin. Piston rods 35 are attached to the yoke 34 and carry pistons 36 working in horizontal 55 cylinders 37 formed in the crank casing of the pump between the cylinders 30. The front ends of all the cylinders 37 are connected by passages 38 formed in the pump casing and the rear ends are all connected 60 by similar passages 39. A passage 40 connects the passages 38 with a port 41 formed in the control valve block 42 which is mounted in a suitable housing formed in the pump casing above the shaft 31. A passage 65 43 leads from the passages 39 to a similar

port 44 of the valve block and between the ports 41 and 44 is a port 45 which may be supplied with fluid pressure from any suitable source, for instance, the circuit of the hydraulic gear through the automatic valve 70 mechanism disclosed in my prior Patent No. 1,206,453 referred to above. Immediately in front of the port 41 is an exhaust or low pressure port 46 and immediately to the rear of the port 44 is a similar exhaust 75 port 47. A piston valve 48 hereinafter termed the control valve, is mounted in a bore 49 of the valve block which intersects the ports 41, 44, 45, 46 and 47 and is provided with heads 50, 51 which exactly close 80 the ports 41 and 44 in one position of the valve 48. It is obvious that when the valve 48 is moved toward the left from the position shown in Fig. 2 the port 41 and consequently the front end of the cylinders 37 85 will be connected with the high pressure port 45, and the port 44 will be connected with its low pressure port 47, so that the fluid pressure from the port 45 will move the yoke 34 to the right as shown in Fig. 2 90 as long as the valve is open, the fluid in the rear ends of the cylinders escaping through the passage 43 and the exhaust port 47. Similarly, when the valve 48 is moved to the right the port 44 will be connected to the high pressure port 45 and the port 41 will be connected to its exhaust port 46 so that the yoke 34 will be moved to the left as long 95 as the valve is open. A floating lever 52 is connected at its middle point with the valve 48 and one end of the lever is connected to the yoke 34 and the other end to a rod 53 100 slidingly mounted in the pump casing at one side of the control block 42. It is obvious 105 that the position of the rod 53 will determine the position of adjustment of the eccentric bushing and consequently the speed and direction of rotation of the driven motor 28. In Fig. 2 I have shown the parts 110 in position for full speed in one direction of rotation. If it be desired to reduce the speed the rod 53 will be moved toward the left, turning the floating lever 52 on its connection with the yoke 34 as a fulcrum and moving the valve 48 to connect the front 115 ends of the adjusting cylinders 37 with the high pressure port 45 thereby causing the yoke 34 to be moved toward the right. As the yoke moves toward the right the end of the floating lever will then turn on its connection with the rod 53 as a fulcrum and close the valve 48 when the yoke has moved as far in the opposite direction as the rod 53 was moved.

In my Patent No. 1,206,453, above referred to, the rod 53 is adapted to be operated directly by the attendant, but when the hydraulic variable speed gear is used to operate gun turrets in the manner disclosed in this application, such direct operation is not 120 125 130

desirable for the reason that the gunner who points the guns cannot be in a position adjacent the speed gear and also because it is very difficult to obtain by direct operation 5 the exceedingly minute adjustments necessary to cause the movement of the turret to exactly compensate for the varying motion of the ship and keep the guns aimed at the target or vessels to be hit. As shown in Fig. 10 2 the control rod 53 projects through the front wall of the pump casing into a cylinder 60 attached thereto. Attached to the rod 53 in the cylinder is a piston head 61 which occupies a position exactly midway of 15 the cylinder when the stroke adjusting mechanism is in its zero or no-stroke position before described. The rod 53 projects through a stuffing box 62 in the front end of the cylinder and between each end of the 20 cylinder and the piston head 61 is provided with collars 63 which act as stops for the inner ends of a flanged sleeve 64 surrounding the rod. The sleeves 64 have inturned flanges 65 which engage the collars 63 and 25 out-turned flanges 66 which form seats for springs 67 arranged between the flanges 66 and the piston head 61. The length of the sleeves 64 is such that when the head 61 is exactly in the middle of the cylinder the 30 flanges 65 just engage the collars 63 and the distance between the flanges 66 is exactly equal to the inside length of the cylinders 60. Pipes 68 and 69 connect with the cylinder 60 on opposite sides of the piston 61 and 35 through these pipes fluid under pressure may be forced as will now be described, to shift the piston 61 and consequently the rod 53 in one direction or the other to give the desired speed in the proper direction of 40 rotation to the motor 28.

In order to properly aim the guns 19 the gunner is preferably stationed on a raised platform 70 supported on the floor of the turret. See Fig. 1. Mounted on a standard 45 71 on the platform 70 is a gear pump 72 with the opposite sides of which the pipes 68 and 69 connect. The pump 72 comprises a casing 73 having two cross shafts 74, 75 to which the pump gears 76, 77 are attached. 50 Washers 78, 79 are mounted on the shafts 74, 75 between the gears and the side plate 80 of the casing so that the wear on the side faces of the gears may be taken up from time to time as may be necessary by thin 55 sheets of packing placed between the washers and the plate 80. A small by-pass from one side to the other of the gear pump is formed by intersecting bores 81, 82, 83 drilled in the pump casing 73 and a needle 60 valve 84 is arranged between the bores 81 and 82 so that the size of the by-pass may be regulated. A small reservoir 85 is connected with the bores of the pipes 68 and 69 by downwardly opening check valves 86, 87, 65 the purpose of which is to permit the pump

to draw from the reservoir whatever fluid may be necessary to compensate for any leakage in the pipe connections or through the bearings of the pump shafts or rod 53. The shaft 74 of the gear 76 projects on each 70 side beyond the casing and to its projecting ends hand wheels 88, 89 having oppositely arranged handles are attached so that the gunner on the platform 70 may operate the pump in either direction at any desired 75 speed.

Whenever there is no pressure on either side of the piston 61, which is always the case when the pump 72 is not operated, the springs 67 hold the piston 61 in its middle 80 position and the stroke adjusting mechanism at zero. Let it be assumed that the parts are in this position and the gunner wishes to turn the turret to bring the guns to bear on the target or other object to be fired at. He 85 has merely to rotate the hand wheels 88, 89 in the proper direction to cause the pump to deliver fluid to the proper pipe, say the pipe 68, to shift the rod 53 in the desired direction. The pressure generated in the pipe 68 90 will depend on the speed of operation of the pump gears and the area of the by-pass as determined by the adjustment of the needle valve 84. If the gears are rotated comparatively slowly, the fluid circulated by the 95 pump can pass through the by-pass at a low pressure and the piston 61 will be shifted but a small distance before the spring 67 on the opposite side of the piston will be compressed sufficiently to exert a pressure equal 100 to the pressure of the fluid and hold the piston stationary in that position as long as the pump gears are operated at that speed. If the gunner wishes to increase the speed 105 of rotation of the turret he increases the speed of operation of the pump 72 which causes the pressure of the fluid to rise to the point necessary for the increased output of the pump to all pass through the needle valve 84. The increased pressure of the 110 fluid will shift the piston 61 farther to the right until the spring 67 is compressed sufficiently to balance the fluid pressure thereby increasing the pump stroke and consequently the speed of the driven motor. If 115 the operator wishes to stop the movement of the turret he holds the hand wheels 88, 89 stationary or releases them, and the compressed spring will return the piston 61 and control rod 53 to zero forcing the fluid from 120 the opposite end of the cylinder 60 through the by-pass. If the operator wishes to reverse the direction of rotation of the turret, he operates the pump 72 to deliver the fluid pressure to the pipe 69 instead of the pipe 68. 125 It will be clear from the above that the speed of operation of the turret is proportional to the speed of operation of the hand pump and not its extent of movement. This is particularly advantageous for the reason 130

that small changes in the speed of a continuously operated member may be made with much greater accuracy than minute changes in the position of a normally stationary member. Further, the gunners are all trained to operate the guns by hand gear in case of damage to the power gear and they are therefore skilled in varying the speed of movement of their operating cranks with 10 accuracy. By means of the needle valve 84 the ratio of the speed of the hand pump and the motor 28 may be adjusted to a nicety to suit the preferences of the individual gunners.

15 A further advantage of my improved control mechanism is that the hand pump may be placed any distance from the hydraulic speed gear without affecting the speed or accuracy of adjustment, as the circulating 20 fluid, preferably oil, is substantially incompressible and the circuit is maintained full at all times by the surplus fluid in the reservoir 85.

While I have shown my improved control 25 apparatus as adapted to control a hydraulic variable speed gear of the type disclosed in my prior patents it will be understood that its use is not limited to such adaptation but that it may be used with other types of 30 speed gears or to control other mechanisms.

I claim—

1. In an apparatus of the class described, the combination of a member to be operated, power driven means for operating said member, movable means for causing said power driven means to operate said member at a speed proportional to the speed of operation of said movable means, and means for adjusting the speed ratio of said operated 40 member and said movable means.

2. The combination of a driving member, a driven member, a hydraulic variable speed gear interposed between these members, and means for controlling the gear 45 comprising a manually rotatable controlling member, and means for altering the gear ratio with changes of speed of movement of the controlling member, whereby the driven member is caused to move at a speed proportionate to the speed of movement of the controlling member.

3. In an apparatus of the class described, the combination of a driving member, a driven member, a variable speed gear interposed between said members, means for controlling said variable speed gear comprising a movable member and means for causing said driven member to move at a speed proportional to the speed of movement of said 55 movable member, and means for varying the speed ratio of said driven member and said movable member.

4. In an apparatus of the class described, the combination of a driving member, a driven member, a variable speed and reverse

gear interposed between said members, means for controlling said gear comprising a movable member and means for causing said driven member to be operated at a speed proportional to the speed of movement of said movable member and in a direction corresponding to its direction of movement and means for varying the speed ratio of said driven member and said movable member.

5. In an apparatus of the class described, the combination of a member to be operated, power driven means for operating said member, and means for controlling said power driven means, comprising a movable element for generating fluid pressure and means operated by said fluid pressure for causing said power driven means to operate said member at a speed proportional to the speed of movement of said movable element.

6. In an apparatus of the class described, the combination of a member to be operated, power driven means for operating said member, means for controlling said power driven means, comprising a movable element for generating fluid pressure and means operated by said fluid pressure for causing said power driven means to operate said member at a speed proportional to the speed of movement of said movable element, and means for varying the speed ratio of said operated member and said movable element.

7. In an apparatus of the class described, the combination of a member to be operated, power driven means for operating said member in opposite directions, and means for controlling said power driven means comprising a movable element for generating fluid pressure and means operated by said fluid pressure for causing said power driven means to drive said member at a speed proportional to the speed of movement of said movable element and in a direction corresponding to its direction of movement.

8. In an apparatus of the class described, the combination of a member to be operated, power driven means for operating said member in opposite directions, means for controlling said power driven means comprising a movable element for generating fluid pressure and means operated by said fluid pressure for causing said power driven means to drive said member at a speed proportional to the speed of movement of said movable element and in a direction corresponding to its direction of movement and means for varying the speed ratio of said operated member and said movable element.

9. In an apparatus of the class described, the combination of a member to be operated, a driving mechanism for operating said member at any speed from zero to a maximum speed, means for controlling said driv-

- ing mechanism comprising a member adjustable to different stationary positions, means operating with said member for causing the changes in speed to correspond with 5 the changes in position of said member, and a manually operatable device for adjusting said member to a position to cause said first mentioned member to be operated at a speed proportional to the speed of operation 10 of said manually operatable device.
10. In an apparatus of the class described, the combination of a member to be operated, a driving mechanism for operating said member at various speeds, means for controlling said driving mechanism comprising a member whose position of adjustment determines the speed of operation of said first mentioned member, fluid pressure operated means for adjusting said member to an extent proportional to the pressure in said means, and a pump having fluid connections with said means and provided with means whereby the pressure generated by said pump is proportional to its speed of operation. 15
- 20
- 25
- 30
- 35
- 40
- 45
- 50
- 55
- 60
- 65
11. In an apparatus of the class described, the combination of a member to be operated, a driving mechanism for operating said member at various speeds, means for controlling said driving mechanism comprising a member whose position of adjustment determines the speed of operation of said first mentioned member, fluid pressure operated means for adjusting said member to an extent proportional to the pressure in said means, a pump having fluid connection with said means and provided with means whereby the pressure generated by said pump is proportional to its speed of operation, and means for varying the ratio of the speed and pressure of said pump.
12. In an apparatus of the class described, the combination of a member to be operated, a driving mechanism for operating said member at various speeds and in opposite directions, means for controlling said driving mechanism comprising a member whose position of adjustment determines the speed and direction of operation of said first mentioned member, fluid pressure operated means for adjusting said member to an extent proportional to the pressure in said means, and a pump having fluid connection with said means and provided with means whereby the pressure generated by said pump is proportional to its speed of operation.
13. In an apparatus of the class described, the combination of a member to be adjusted in opposite directions, means for yieldingly holding said member in an intermediate neutral position, and means, comprising a manually operatable device, for adjusting said member away from its normal position to an extent proportional to the speed of op- 10
- eration of said device and in a direction corresponding to its direction of operation.
14. In an apparatus of the class described, the combination of a member to be adjusted in opposite directions, means for yieldingly holding said member in an intermediate neutral position, means, comprising a manually operatable device, for adjusting said member away from its normal position to an extent proportional to the speed of operation of said device and in a direction corresponding to its direction of operation, and means for varying the ratio between the speed of operation of said device and the extent of operation of said member. 15
15. In an apparatus of the class described, the combination of a member to be adjusted in opposite directions, means for adjusting said member comprising a cylinder, a piston, springs in said cylinder on opposite sides of said piston, a pump for generating fluid pressure in proportion to its speed of operation and fluid transmitting connections between the opposite sides of said pump and the opposite ends of said cylinder. 20
16. In an apparatus of the class described, the combination of a hydraulic variable speed gear device having an engine section and a pump section, and also having a regulator for governing the action of the pump section, means for moving said regulator from a neutral or pump stopping position to a pump starting position to thereby start said pump and therefore said engine, and independent means for returning said regulator to said neutral position. 25
17. In an apparatus of the class described, the combination of a hydraulic variable speed device comprising means for starting the same, and independent means active in opposition to said other means and tending to stop said device. 30
18. In an apparatus of the class described, the combination of a hydraulic variable speed gear device comprising manually governed means for starting said device, and independent means automatically thrown into action when said device is started, active in opposition to said other means and tending to stop said device. 35
19. In an apparatus of the class described, the combination of a hydraulic variable speed gear device comprising a variable stroke pump, a motor driven by said pump at various speeds depending upon the adjustment of the stroke of said pump, and means for adjusting said pump stroke comprising a member to be manually rotated, and connections between said member and said pump for producing alterations in pump stroke upon changes in speed of operation of said member in such manner that the speed of the driven motor is maintained at a predetermined ratio to the speed of rotation of said member. 40

- 6
20. In an apparatus of the class described, the combination of a hydraulic variable speed gear device comprising a variable stroke pump and a motor operated by the fluid delivered from the pump, means for varying the stroke of the pump comprising a member adjustable to different fixed positions to correspondingly vary the pump stroke, and means for operating said member comprising a manually rotatable part, and connections between said member and said part whereby the speed of rotation of

said part so shifts the position of said member as to maintain the speed of the motor at a predetermined ratio to the speed of movement of said part. 15

In testimony whereof, I have signed my name to this specification in the presence of two subscribing witnesses, this 7th day of October, 1911.

CHARLES MATTHEWS MANLY.
